FIG. 4

FIG. 1

FIG. 2

FIG. 3

FIGURE 1 is a side elevational view of a composite bottle showing my new design.

FIGURE 2 is a top plan view thereof.

FIGURE 3 is a perspective view thereof on a reduced scale.

FIGURE 4 is a fragmentary cross-sectional view taken through the center of the upper portion of the bottle.

The dominant features of our design reside in the portions shown in full lines.

The top portion of the bottle is shaded to indicate contrast in surface texture.

We claim:

The ornamental design for a composite bottle, substan-
tially as shown and described.
